CLAIM

The ornamental design for a dryer comb concentrator
attachment, as shown and described.

DESCRIPTION

FIG. 1 is a right side elevational view of a dryer comb
concentrator attachment showing my new design;

FIG. 2 is a bottom plan view thereof;

FIG. 3 is a top plan view thereof;

FIG. 4 is a front elevational view thereof;

FIG. 5 is a rear elevational view of a dryer comb con-
centrator attachment showing a modified form of my
new design with fine teeth, and

FIG. 6 is a right side elevational view thereof.
